ATTORNEY

UNITED STATES PATENT OFFICE.

JOHN A. BRAGAW, OF ALBANY, NEW YORK, ASSIGNOR OF ONE-HALF TO
ALFRED EUGENE STANTON, OF MONTROSE, PENNSYLVANIA.

SIGNAL-LANTERN.

SPECIFICATION forming part of Letters Patent No. 361,808, dated April 26, 1887.

Application filed June 22, 1886. Serial No. 205,932. (No model.)

To all whom it may concern:

Be it known that I, JOHN A. BRAGAW, a resident of Albany, in the county of Albany and State of New York, have invented an Improvement in Signalizing-Lantern, of which the following is a full, clear, and exact description, reference being made to the accompanying drawings, in which—

Figure 1 is a vertical central section of my improvement, the lantern itself being in side view. Fig. 2 is a vertical central section of the improved screen, showing it lowered on a lantern, which is in side view.

The object of this invention is to provide a lantern—such as is used by switchmen and the like on railroads by watchmen and station-masters—with means for changing the color of the light. Lanterns for that object have heretofore been made, some having reversible swiveled oil-vessels, and others glass slides; but none have come into general use, as far as I am aware, because of their inherent defects.

My invention consists in combining with an ordinary or suitable lantern having a glass cylinder or globe a flexible and preferably extensible outer screen of translucent substance, which, when expanded and brought in line with the light, will cause the color of its rays to be changed into red, green, or other tint, while a white light will be produced when said screen is contracted and not in line with the light.

In the drawings, the letter A represents a suitable lantern, in which *a* is the wick-tube, *b* the globe or cylinder, *d* the base, and *e* the cap. *B* is my improved flexible screen, which is a cylindrical open-ended structure of thin

india-rubber, silk, or other suitable fabric. This cylindrical screen, when made extensible and contractible, will, when expanded to its full height, as in Fig. 1, surround the light of the lantern and change the color thereof, while when contracted, as shown by the zigzag lines in Fig. 2, it will be below the wick-tube and not interfere with the color of the light. When raised, it is held in position by suitable hooks, *f*, on a ring, *g*.

The manner in which this lantern is to be used can be readily understood. A person swinging or holding it for the purpose of giving a certain signal—say of “safety” or “danger” on a railroad—will, when the screen is out of line with the light, indicate “safety.” If “danger” is to be indicated, the attendant will be in position to suddenly bring the movable screen around the light for the purpose of producing the change in the color of the rays.

I do not confine myself to any substance from which the flexible screen *B* is made, nor to any particular device for holding it in the upper and lower positions.

I claim—

In a lantern, the combination of a lamp-body, the burner, the globe, the vertically expandable and contractible translucent screen inclosing the burner, and the screen-supporting frame, substantially as herein shown and described.

JOHN A. BRAGAW.
